NEUROLOGICAL DIAGNOSTIC UNIT

Campbell D. Harris, Mountain Lakes, N. J., assignor to
Radio Frequency Laboratories, Inc., Boonton, N. J., a
corporation of New Jersey

Application July 6, 1954, Serial No. 31,280

Term of patent 14 years

(Cl. D83—1)

The figure is a top perspective view of a neurological diagnostic unit showing my new design.

The two undisclosed sides of the apparatus are plain.

I claim:

The ornamental design for a neurological diagnostic unit, substantially as shown and described.
